UNITED STATES PATENT OFFICE.

WILLARD A. INGALLS, OF SOUTH BEND, WASHINGTON, ASSIGNOR OF ONE-HALF TO THEODORE PEARSON, OF SAME PLACE.

SEPARABLE BUTTON.

SPECIFICATION forming part of Letters Patent No. 596,163, dated December 28, 1897.

(Application filed July 8, 1897. Serial No. 643,824. (No model.)

To all whom it may concern:

Be it known that I, WILLARD A. INGALLS, a citizen of the United States, residing at South Bend, in the county of Pacific and State of Washington, have invented certain new and useful Improvements in Separable Buttons; and I do declare the following to be a full, clear, and exact description of the invention, such as will enable others skilled in the art to which it appertains to make and use the same.

My invention relates to a novel form of separable button, and more particularly to that class of jewelry-buttons intended for collars, cuffs, and the like; and the object is to provide a simple and efficient button of this class.

To this end the invention consists in the construction, combination, and arrangement of the same, as will be hereinafter more fully described, and particularly pointed out in the claim.

In the accompanying drawings the same reference-characters indicate the same parts of the invention.

Figure 1 is a perspective view, partly in section, of my improved separable button with the parts assembled. Fig. 2 is a similar view with the back and head separated. Fig. 3 is a transverse section through the hollow shank 2.

1 represents the back of the button, and 2 the integral hollow cylindrical shank, which is formed with an internal flange 3, and 4 represents a longitudinal radial tooth or rib fixed to the inner wall of the shank 2 contiguous to the flange 3.

5 represents the button-head, and it is provided with a solid stem 6, terminating in a conical point 7, from which an integral spring-pawl 8 extends divergently from the stem 6. The free end of the pawl 8 terminates in a tooth 9, which is adapted to engage the flange 3 in the hollow shank 2 to hold the head in

place in said shank. The conical end 7 of the stem 6 snugly fits a correspondingly formed recess 10 in the shank 2, which serves to hold the solid stem 6 in place in said shank.

The rib 4 is preferably V-shaped in cross-section, so that the spring-tooth 9 may ride upon either of its inclined sides to carry it out of the path of the flange 3 and thereby release it from the back portion 1 when it is desired to separate the button.

Although I have specifically described the construction and relative arrangement of the several elements of my invention, I do not desire to be confined to the same, as such changes or modifications may be made as clearly fall within the scope of my invention without departing from the spirit thereof.

Having thus fully described my invention, what I claim as new and useful, and desire to secure by Letters Patent of the United States, is—

A separable button comprising the back 65 having the integral tubular stem formed at its lower end with a conical seat and at its upper end with an inwardly-projecting continuous annular flange, and with an internal rib provided with inclined sides, and a head 70 provided with a stem tangentially slit longitudinally its length from its upper to its lower end to form a spring-arm terminating at its upper separated end in a tooth adapted to engage the inwardly-projecting flange, the 75 conical end of said stem resting in the conical seat of the shank, whereby lateral or wobbling motion of one part of the button with respect to the other part is prevented, substantially as set forth.

In testimony whereof I hereunto affix my signature in presence of two witnesses.

WILLARD A. INGALLS.
